UNITED STATES PATENT OFFICE.

GUSTAV A. KELCH, OF NEW YORK, N. Y.

DESIGN FOR AN ARTICLE OF MANUFACTURE.

47,958.

Specification for Design.

Patented Oct. 12, 1915.

Application filed July 22, 1915. Serial No. 41,405. Term of patent 3½ years.

To all whom it may concern:

Be it known that I, GUSTAV A. KELCH, a citizen of the United States, and a resident of the city of New York, borough of Manhattan, in the county and State of New York, have invented a new, original, and ornamental Design for an Article of Manufacture, of which the following is a specification, reference being had to the accompanying drawing, forming a part thereof.

The figure is a face view of my new design to be applied to an article of manufacture.

I claim:

The ornamental design for an article of manufacture as shown.

GUSTAV A. KELCH.

Witnesses:

THEO. G. HOSTER,
PHILIP D. ROLLHAUS.
